UNITED STATES PATENT OFFICE.

MARY MYRTLE BUCK, OF MACHIAS, NEW YORK, AND JOHN F. MALLINCKRODT, OF DENVER, COLORADO; SAID MALLINCKRODT ASSIGNOR TO SAID BUCK.

CURLING-IRON HEATER.

SPECIFICATION forming part of Letters Patent No. 727,893, dated May 12, 1903.

Application filed November 23, 1901. Serial No. 83,453. (No model.)

To all whom it may concern:

Be it known that we, MARY MYRTLE BUCK, of Machias, in the county of Cattaraugus and State of New York, and JOHN F. MALLINCKRODT, of Denver, in the county of Arapahoe and State of Colorado, have invented certain new and useful Improvements in Curling-Iron Heaters; and we do hereby declare the following to be a full, clear, and exact description of the invention, such as will enable others skilled in the art to which it appertains to make and use the same.

Our invention relates to an improvement in heaters for curling-irons, and more particularly to a device of this character which will be coin-operated to permit the use of heated irons for a predetermined length of time, the object of the invention being to provide a curling-iron heater which can be placed in public places for the convenience of travelers or transients.

A further object is to provide a curling-iron heater which will be small and compact, neat and attractive in appearance, comparatively cheap to manufacture, and of great convenience to the public at large.

With these objects in view the invention consists in certain novel features of construction and combinations and arrangements of parts, as will be more fully hereinafter described, and pointed out in the claims.

In the accompanying drawings, Figure 1 is a view illustrating our improvements. Fig. 2 is a side view with part of the casing removed. Fig. 3 is a plan view with the top and parts carried thereby removed. Figs. 4 and 5 are views of opposite ends of the device with parts of the same removed; and Figs. 6, 7, and 8 are views of various details of construction.

The working parts of our improved device are inclosed in a casing comprising top and bottom plates 1 2, front and rear plates 3, and end plates 4, all secured together by bolts, screws, and rivets, as shown, forming a rectangular casing ornamented in any desired manner. In the casing, preferably near one end thereof, but arranged in alinement in the longitudinal center of the casing, are three

(more or less) tubular heating-chambers 5, supported at their ends in alined rings 6 integral with top and bottom plates 1 2. These tubular heating-chambers are preferably of metal, around which a thin asbestos insulation 7 is provided for an electrical conductor 8, coiled around the same and inclosed in a covering of plaster-of-paris 9, openings being provided in the top or cover 1 for the insertion of the curling-irons into the tubes, said openings being disposed eccentrically to the tubes to permit the irons to be effectually locked in the tubes, as will now be explained.

The tubes 5 are each provided between their ends with an opening to receive the short and flattened end of a counterweighted locking-lever 10, pivoted near its end between lugs 11 on the tube and whose weight normally holds the inner end, which is flattened or has a flat plate secured thereto, against the curling-iron, thus forming, in effect, a wedge, which will effectually prevent the removal of the iron until the weighted end of the locking-lever is raised, but will not interfere with the downward movement of the iron, thus permitting its insertion after the levers have fallen to their locking position.

To raise the weighted ends of the locking-levers 10 to a position to permit the withdrawal of the irons, we provide a series of fingers 12 below the same and projecting at right angles to a shaft 13, supported in standards 14, secured to the base-plate, and provided at one end with a bifurcated arm 15, encompassing a push-rod 16, projecting up through the top plate 1 and provided at its upper end with a button 17 and between its ends with a collar 18, adapted when the rod 16 is depressed to engage the arm 15, force it downward, thus partially turning shaft 13 to raise the fingers 12 and elevate the weighted ends of the locking-levers 10 and permit the withdrawal and insertion of the irons just as long as the push-bar remains depressed. The downward movement of push-rod 16 also forces the collar 18 against the inclined or cam face of a hook 19 on the upper end of a lever 20, having counterweighted arm 20^a, normally holding said hook against the collar, and this lever is se-

cured on a shaft 21, supported in suitable bearings on the base-plate 2, thus moving the lever 20 outward and partially turning the shaft 21, the collar 18 when moved to its lowest position catching below the hook 19 and being held in such position for a predetermined length of time, as will now be explained.

Supported in a frame 22 at one end of the 10 casing is a suitable clockwork, operated by a spring 23 on an angular spindle 24, projecting through the end of the casing for the reception of a key to wind the same. This 15 clockwork mechanism is provided with the usual escapement-wheel 25 and with a time-wheel 26, the latter made with a series of inclined teeth and notches 27 at the junction of said teeth. An elongated dog or catch 28, secured on shaft 21, is normally held in one of 20 the notches 27 by the counterweighted arm 20^a; but when the shaft 21 is partially turned by the collar 18 engaging the cam-face of hook 19 this dog 28 is moved out of a notch 27 and the escapement-wheel 25 started by an 25 arm or pin 29 on the dog, thus starting the clockwork and turning the time-wheel 26 far enough to prevent the entrance of the dog into the notch, but presenting to the dog the inclined or cam edge of a tooth, which as the 30 wheel turns moves the dog outward, thus slightly turning shaft 21 and moving lever 20 until just as the dog reaches the extremity of the tooth the hook 19 will be moved far enough to release the collar 18, permitting the 35 push-rod 16 to be raised by a counterweighted lever 30, fulcrumed between its ends on an upright 31, secured to the base-plate 2, and engaging an adjustable collar 32 on the rod 16, which collar also serves as a stop, striking 40 against the top plate 1 and limiting the upward movement of the rod. When the time-wheel 26 turns far enough, this turning being timed to suit the length of time for which the irons are to be used, (five minutes being 45 preferably allowed, and this time must elapse before the tooth will move along the dog,) the dog will spring into the next notch and stop the clock mechanism and hold it until the push-rod is again depressed.

50 To prevent the operation of push-rod 16, we provide a coin-operated mechanism comprising a vertical rod 33, having a weighted arm 35 and pivoted at its lower end, as shown, and provided at its upper end with a notch 55 or shoulder 34 to be moved below the collar 18 by the weighted arm 35 and preventing the downward movement of the push-rod. This rod 33 is provided at its upper end with an arm 36, extending at right angles thereto and 60 carrying at its free end a basket or coin-receptacle 37, into which the coin is guided by a chute 38, communicating with a slot in the top plate, and when the coin falls into the receptacle 37 it will overbalance the weighted 65 arm 35 and draw the shoulder 34 from beneath

collar 18, thus permitting the rod 16 to be depressed.

On arm 36, near shoulder 34, a vertical fork 39 is located and has pivotally supported therein a trip 40 in the path of the collar 32. 70 To this trip 40 an H-shaped bracket 41 is pivoted and carries in its bifurcated lower portion an arm 42, projecting into the receptacle and having a concave strip 43 to engage one edge of the coin when the latter rests in the 75 basket, and it will be seen that when the rod 16 is depressed the collar 32 will strike trip 40, swinging it on its pivot and moving bracket 41 to thrust arm 42 forward, thus ejecting the coin from the receptacle and compelling the 80 same to fall into a drawer 44, provided for the purpose, and hence freeing arm 36 from the weight of the coin and permitting the counterweight 35 to return the shoulder 34 as near as possible to its position to lock the collar 18. 85 A weak spring 45 is secured to the rod 33 and bears at its free end against a pin 46 on arm 42 for returning the latter and the trip to their normal positions.

The operation of our improvements is as 90 follows: When it is desired to use the curling-irons, a nickel or the proper coin, as the case may be, is dropped into the chute 38 and falls into receptacle 37, thus overbalancing weight 35 and moving the shoulder 34 from beneath 95 collar 18. The push-rod 16 is now depressed, moving the lever 20, through the medium of the cam-faced hook 19, to release the time-wheel 26 and start the clockwork, as above described. This downward movement of the 100 rod 16, through the medium of the collar 18, engaging the arm 15 on shaft 13, and hence by means of the fingers 12 raises the weighted locking-levers 10, permitting the withdrawal and use of the irons for a predetermined 105 time (say five minutes) or, in other words, until the time-wheel 26 shall have moved a distance of one tooth, as heretofore explained.

Instead of heating the tubes 5 by electricity we might heat them by gas, oil, or any other 110 means, and hence we do not wish to be limited to the use of electricity, and various changes might be resorted to in the general form and arrangement of the several parts described without departing from the spirit 115 and scope of our invention, and hence we would have it understood that we do not wish to limit ourselves to the precise details set forth, but consider ourselves at liberty to make such slight changes and alterations as 120 fairly fall within the spirit and scope of our invention.

Having fully described our invention, what we claim as new, and desire to secure by Letters Patent, is—

1. In a curling-iron heater, the combination of the heating-receptacle and coin-operated means for engaging an iron and controlling the withdrawal of the iron from the receptacle.

2. In a curling-iron heater, the combination of a heating-receptacle, means for engaging and locking an iron therein, and coin-operated mechanism for controlling said locking means.
3. In a curling-iron heater, the combination with a heating-receptacle for an iron, of means for engaging and locking an iron therein, means for releasing said locking means and coin-operated mechanism to prevent the operation of said last-mentioned means.
4. In a curling-iron heater, the combination with a heating-receptacle for an iron, of means for locking an iron therein, means for releasing said locking means, coin-operated mechanism to prevent the operation of said last-mentioned means, and automatic devices for preventing the return of the locking means to their locking position for a predetermined time.
5. In a curling-iron heater, the combination with a heating-receptacle for an iron, of a locking-lever for engaging and locking an iron therein, a push-rod to unlock said lever, and coin-operated mechanism to prevent the operation of the push-rod.
6. In a curling-iron heater, the combination with a heating-receptacle for an iron, a locking-lever for locking the iron in the receptacle, a push-rod for moving the lever to its unlocked position, coin-operated mechanism normally preventing the operation of the push-rod, and automatic mechanism for timing the return of the locking-lever to its locking position.
7. In a curling-iron heater, the combination with a heating-receptacle for the iron, of means for locking the iron in said receptacle, a push-rod releasing the locking mechanism when the rod is depressed, a catch or hook holding the rod depressed, automatic mechanism for timing the movement of the hook to release the push-rod, and coin-operated mechanism normally preventing the depression of said push-rod.
8. In a curling-iron heater, the combination with heating-receptacles for irons, of weighted locking-levers normally locking the irons in the receptacles, a push-rod, devices operated by the push-rod, when the latter is depressed, to move all of the locking-levers out of their locking positions, a hook holding the push-rod depressed, automatic mechanism for timing the movement of the hook to release the push-rod and permit its upward or outward movement, and coin-operated mechanism normally preventing the depression of said push-rod.
9. In a curling-iron heater, the combination with a heating-receptacle for the iron, means for locking the iron in the receptacle, and a push-rod, when depressed, operating the locking mechanism to release the iron, coin-operated mechanism normally preventing the depression of the push-rod, a catch to hold the push-rod depressed, a time-wheel, clock-work mechanism for turning said time-wheel, a dog to stop said wheel but released therefrom by the depression of the push-rod and serving to release the hook from the push-rod when the time-wheel has moved a predetermined distance.
10. In a curling-iron heater, the combination with a heating-receptacle for an iron, and means for locking the iron in the receptacle, of a push-rod for releasing said locking means when the push-rod is depressed, a collar on the push-rod, a counterweighted pivoted rod having a shoulder normally held beneath the collar to prevent the depression of the push-rod, a coin-receptacle carried by the pivoted rod to receive a coin and move the shoulder from the path of the collar and means operated by the push-rod for ejecting the coin from the receptacle when the rod is depressed.
11. In a curling-iron heater, the combination with a heating-receptacle for an iron and means for locking the iron in said receptacle, of a push-rod adapted when depressed to release said locking means, a hook for holding the push-rod depressed, a toothed time-wheel, having notches at the juncture of its teeth, a motor for turning said time-wheel, a dog adapted to move into one of said notches and lock the time-wheel and devices between the dog and hook for transmitting motion to move the latter and release the push-rod when the time-wheel moves a predetermined distance.
12. In a curling-iron heater, the combination with a heating-receptacle for an iron, and means for locking an iron in said receptacle of a push-rod adapted when depressed to release said locking means, a collar on said push-rod, a pivoted rod having a shoulder normally below said collar, a coin-receptacle carried by the pivoted rod and adapted when a coin is received therein to move the shoulder from beneath the collar to permit the depression of the push-rod, and mechanism operated by a second collar on the push-rod for ejecting the coin from the receptacle when the push-rod is depressed.
13. In a curling-iron heater, the combination with a casing of a series of tubular iron-receptacles in said casing communicating with openings in the casing for the reception of irons, an insulating-sheet around said receptacles, electricity-conducting wire coiled about said receptacles, a plaster-of-paris covering over said coils of wire, means for locking the irons in the receptacles, a push-rod for releasing said locking mechanism and coin-operated mechanism normally preventing the operation of the push-rod.
14. In a curling-iron heater, the combination with a casing, and a heating-receptacle therein, said casing having an opening therein to permit the insertion of an iron into said receptacle, of a locking-lever having a flattened end and pivoted near its flattened end.

and projecting into said receptacle, a weight on the long end of said lever to normally hold the flattened end of the lever in an inclined position and against an iron to prevent the removal of the latter, a push-rod adapted to raise the weighted end of the lever and release the iron when the push-rod is depressed, and coin-operated mechanism normally preventing the depression of said push-rod.
